UNITED STATES PATENT OFFICE.

FRANKLIN O. ANDREWS, OF WILLOUGHBY, OHIO.

SASH-LOCK.

No. 804,994.

Specification of Letters Patent.

Patented Nov. 21, 1905.

Application filed April 14, 1905. Serial No. 255,636.

To all whom it may concern:

Be it known that I, FRANKLIN O. ANDREWS, a citizen of the United States of America, residing at Willoughby, in the county of Lake and 5 State of Ohio, have invented certain new and useful Improvements in Sash-Locks; and I hereby declare the following to be a full, clear, and exact description of the invention, such as will enable others skilled in the art to which 10 it pertains to make and use the same.

This invention relates to improvements in sash-locks.

The object of this invention is to provide a sash-lock which is applied to the upper sash 15 of a window and which is arranged and secured in place in such a manner that it cannot be loosened or rendered inoperative by wedges or tools applied in under the lower end of the lower sash to force the lower sash 20 upwardly.

With this object in view and to the end of realizing other advantages hereinafter appearing this invention consists in certain meritorious features of construction and combinations of parts hereinafter described, and pointed out in the claims.

In the accompanying drawings, Figure 1 is a side elevation of a portion of the adjacent portion of the two sashes of a window. Fig. 30 2 is a vertical section on line 2 2, Fig. 1, looking in the direction indicated by the arrow. Fig. 3 is a vertical section corresponding with Fig. 2, except that in Fig. 3 the sash-locking stop of the sash-lock is shown in its operative 35 position, whereas in Fig. 2 the said stop is shown in its inoperative position.

Referring to the drawings, A designates a portion of a window-casing; B, the upper sash; D, the lower sash; b, one of the stiles or side 40 members of the framework of the upper sash, and d the framework of the lower sash.

My improved sash-lock comprises a metal case G, which occupies a recess made in the inner side of the stile or side member b of the 45 framework of the upper sash. The case G is provided with an upwardly-projecting ear 6 and a depending ear 7, arranged at the upper end and lower end, respectively, of the case G. The ears 6 and 7 are each provided with 50 a horizontally-arranged hole 8, which extends horizontally through the respective ear and is countersunk at its outer end to receive the countersunk head h of a screw H, which extends through the said hole and is screwed into 55 the stile b. It will be observed, therefore, that the case G is removably secured to the

framework of the upper sash by screws which are screwed horizontally into the said framework from the inner side of the said sash. The case G is arranged with its ears 6 and 7 60 flush with the inner side of the upper sash, so as to avoid interference with the movement of the lower sash.

Within the chamber g of the case G is arranged a stop K, which is pivoted at its upper 65 end to the case G, as at k, horizontally and at a right angle to the screws H. The stop K is capable therefore of swinging in a vertical plane and extends from the upper end to the lower end of the chamber g of the case G. 70 The chamber g is open at its forward side—that is, at the inner side of the upper sash—to accommodate the swinging of the stop K forwardly over the upper end of the lower sash when the latter is in its lower position, 75 and the stop K is operative or inoperative according as it is in its forwardly-swung or rearwardly-swung position.

The arrangement of the parts is such that the stop K in its rearwardly-swung position 80 is contained wholly within the chamber g of the case G and in its forwardly-swung position overlaps the upper end of the framework of the lower sash. The arrangement of the case G relative to the lower sash is prefer- 85 ably such that the bottom wall of the chamber g of the said case is flush with the upper edge of the framework of the lower sash in the lower position of the said sash when the sashes are closed. 90

The lower edge of the stop K extends concentrically of the axis of the stop, and the upper end of the stop has such arrangement relative to the top wall of the chamber g of the case G that the said end of the stop in the 95 forwardly-swung and operative position of the stop abuts against the top wall of the said chamber and prevents any strain upon the pivot k by an attempt to lift the lower sash when the stop is in its operative position. 100

Preferably the upper rail or top member of the framework of the lower sash is provided with a metal plate J, which is secured to the said framework and has a top surface arranged concentrically of the axis of the stop 105 K and next to the sweep of the lower end of the stop.

A suitably-applied spiral spring L acts to retain the stop K in its forwardly-swung and operative position. The spring L abuts at 110 one end against the rear wall of the chamber g and abuts at its other end against the end

wall of a recess 10, formed in the inner side of the stop.

- Means for locking the stop K in its rearwardly-swung and inoperative position is provided and comprises a latch R, which is pivoted, as at r, horizontally and parallel with the axis of the stop K and projects rearwardly. The latch R is provided at its rear and free end with an upwardly-projecting member 12. The latch R is provided at its forward and pivoted end with an upwardly-projecting arm 13, which is arranged longitudinally of the stop K. The stop K is suitably slotted, as at 14, to accommodate the location and operation of the latch R and its arm 13. The rear wall of the case G is slotted, as at 15, to accommodate the extension of the latch R through the said wall and to accommodate the operation of the latch. The arrangement of the parts is such that in the rearwardly-swung and inoperative position of the stop K the latch R extends through the rear wall of the case G, and the upwardly-projecting member 12 of the said latch overlaps the exterior of the said wall, and the stile b of the framework of the upper sash is cut away exteriorly of the said wall, as at 16, to accommodate the location and operation of the latch R. A suitably-applied spiral spring Q acts to retain the latch R in its operative position, wherein the upwardly-projecting member of the said latch, as already indicated, overlaps the exterior of the rear wall of the case G. The spring Q is confined, preferably, between the inner side of the arm 13 and the rear wall of the case G, and the stop K is provided with a hole 17, which extends rearwardly through the stop from the upper portion of the slot 14 to accommodate the location and operation of the said spring.

The upwardly-projecting member 12 of the latch R is beveled, so as to form an incline 18 upon the rear side of the said member, which incline slopes upwardly and forwardly.

By the construction hereinbefore described it will be observed that the latch R in the rearwardly-swung and operative position of the stop K locks the said stop in the said position, and that by pressing rearwardly against the forward side of the arm 13 of the latch R against the action of the spring Q to disengage the projecting member 12 of the said latch from the exterior of the rear wall of the case G the stop K is rendered free to swing forwardly and is then at once swung forwardly by the action of the spring L.

To actuate the stop K from its forwardly-swung and operative position into its rearwardly-swung and inoperative position, it is only necessary to actuate the said stop by pressure exerted upon its forward side rearwardly against the action of the spring L until the upwardly-projecting member 12 of the latch R is brought exteriorly of the rear wall of the

case G. The incline 18 upon the said member 12 during the actuation of the stop K into its inoperative position comes into engagement with the top wall of the slot 15 in the rear wall of the case G, whereupon the latch R is depressed against the action of the spring Q to accommodate the passage of the latch member 12 through the said slot until the said latch member is brought exteriorly of the said wall, whereupon the said spring acts to swing the latch upwardly to cause the latch member 12 to overlap the exterior of the rear wall of the case, and thereby lock the stop K in its rearwardly-swung and operative position.

What I claim is—

1. A sash-lock comprising a case adapted to be inserted within the framework of the upper sash of a window, which case is open at its forward side and provided in the rear wall thereof between the upper and lower ends of the chamber of the case with a slot; a stop arranged within the said chamber and pivoted at one end to the case, which stop is arranged to swing forwardly and rearwardly and contained wholly within the chamber and inoperative or operative according as it is in its rearwardly-swung or forwardly-swung position; means acting to retain the stop in its forwardly-swung and operative position; a latch arranged within and pivoted to the stop and extending rearwardly through the aforesaid slot in the inoperative position of the stop and provided, at its rear end, with a projecting member overlapping the exterior of the rear wall of the case in the last-mentioned position of the stop, and means acting to retain the latch in its operative position, said stop having in its face a slot to receive the latch.

2. A sash-lock comprising a case adapted to be inserted within the framework of the upper sash of a window, which case is open at its forward side and provided in the rear wall thereof between the upper and lower ends of the chamber of the case with a slot; a stop arranged within the said chamber and pivoted at one end to the case, which stop is arranged to swing forwardly and rearwardly and inoperative or operative according as it is in its rearwardly-swung or forwardly-swung position; a suitably-applied spring acting to retain the stop in its forwardly-swung and operative position; a latch arranged within and pivoted to the stop and extending rearwardly through the aforesaid slot in inoperative position of the stop and provided, at its rear end, with a projecting member overlapping the exterior of the rear wall of the case in the last-mentioned position of the stop, and means acting to retain the latch in its operative position, said stop having in its face a slot to receive the latch.

3. A sash-lock comprising a case adapted to be inserted within the framework of the upper sash of a window, which case is open at its forward side and provided in the rear wall

- thereof between the upper and lower ends of the chamber of the case with a slot; a stop arranged within the said chamber and pivoted at one end to the case, which stop is arranged 5 to swing forwardly and rearwardly and inoperative or operative according as it is in its rearwardly-swung or forwardly-swung position; means acting to retain the stop in its forwardly-swung and operative position; a latch pivoted to the stop parallel with the axis of the stop and extending rearwardly through the aforesaid slot in the inoperative position of the stop and provided, at its rear end, with a projecting member overlapping the exterior 10 of the rear wall of the case in the last-mentioned position of the stop, and means acting to retain the latch in its operative position, said stop having in its face a slot to receive the latch.
- 20 4. A sash-lock comprising a case adapted to be inserted within the framework of the upper sash of a window, which case is open at its forward side and provided in the rear wall thereof between the upper and lower ends of 25 the chamber of the case with a slot; a stop arranged within the said chamber and pivoted at its upper end to the case, which stop is arranged to swing forwardly and rearwardly and inoperative or operative according as it is 30 in its rearwardly-swung or forwardly-swung position; means acting to retain the stop in its forwardly-swung and operative position; a latch pivoted to the stop parallel with the axis of the stop and extending rearwardly 35 through the aforesaid slot in the inoperative position of the stop and provided, at its rear end, with an upwardly-projecting member overlapping the exterior of the rear wall of the case in the last-mentioned position of the 40 stop, and means acting to retain the latch in its operative position, said stop having in its face a slot to receive the latch.
5. A sash-lock comprising a case adapted to be inserted within the framework of the upper 45 sash of a window, which case is open at its forward side and provided in the rear wall thereof between the upper and lower ends of the chamber of the case with a slot; a stop arranged within the said chamber and pivoted 50 at one end to the case, which stop is arranged to swing forwardly and rearwardly and inoperative or operative according as it is in its rearwardly-swung or forwardly-swung position; means acting to retain the stop in its 55 forwardly-swung and operative position; a latch pivoted to the stop parallel with the axis of the stop and extending rearwardly through the aforesaid slot in the inoperative position of the stop and provided, at its rear 60 end, with a projecting member overlapping the exterior of the rear wall of the case in the last-mentioned position of the stop, which latch is provided, at its forward end, with an arm, and a suitably-applied spring acting to
- retain the latch in its operative position and 65 confined between the rear side of the said arm and the rear wall of the case, said stop having in its face a slot to receive the latch.
6. The combination, with the upper sash and the lower sash of a window, of a case embedded in the forward side of the framework of the upper sash and open at the inner side of the sash, which case is provided in its rear wall with a slot and has two ears arranged at opposite ends respectively of the case; screws 70 screwed horizontally through the said ears into the aforesaid framework and having their heads countersunk in the said ears; a stop arranged within the chamber of the case and pivoted at one end to the case, which stop is 75 capable of being swung forwardly and rearwardly and is inoperative or overlaps the upper end of the framework of the lower sash according as the stop is in its rearwardly-swung or forwardly-swung position; means 80 for retaining the stop in its forwardly-swung and operative position; a latch pivoted to the stop and extending through the aforesaid slot in the inoperative position of the stop, which latch is provided, at its rear end, with a projecting member arranged to overlap the exterior of the rear wall of the case in the last-mentioned position of the stop, and means 85 acting to retain the latch in its operative position, and the stop being slotted to accommodate the location and operation of the latch, and the framework of the upper sash being 90 cut away to accommodate the operation of the aforesaid projecting member of the latch.
7. The combination, with the upper sash and the lower sash of a window, of a case embedded in the forward side of the framework of the upper sash and open at the inner side of the sash, which case is provided in its rear wall with a slot; a stop arranged within the 95 chamber of the case and pivoted at one end to the case, which stop is capable of being 100 swung forwardly and rearwardly and is inoperative or overlaps the upper end of the framework of the lower sash according as the stop is in its rearwardly-swung or forwardly-swung position; means acting to retain the stop in its forwardly-swung and operative position; a latch pivoted to the stop and extending 105 through the aforesaid slot in the inoperative position of the stop, which latch is provided, at its rear end, with a projecting member arranged to overlap the exterior of the rear wall of the case in the last-mentioned position of the stop, and means for retaining 110 the latch in its operative position, said stop having in its face a slot to receive the latch.
- In testimony whereof I sign the foregoing specification in the presence of two witnesses:
- FRANKLIN O. ANDREWS.
- Witnesses:
- C. H. DORER,
N. L. McDONNELL.
